UNITED STATES PATENT OFFICE.

DAVID ZAIDEN, OF EAST ORANGE, NEW JERSEY.

MECHANICAL GEISHA DOLL.

1,411,825.

Specification of Letters Patent.

Patented Apr. 4, 1922.

Application filed May 17, 1921. Serial No. 470,264.

To all whom it may concern:

Be it known that I, DAVID ZAIDEN, a citizen of Russia, residing at East Orange, in the county of Essex and State of New Jersey, 5 have invented certain new and useful Improvements in Mechanical Geisha Dolls; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 The present invention relates, generally, to improvements in dolls; and the invention has reference, more particularly, to a novel mechanical doll representing a Japanese geisha and adapted to perform the movements of fanning itself, while at the same time revolving about on its feet.

20 The invention has for its principal object to provide a novel construction of doll with which is combined a mechanical motor device mounted in a novel manner in connection therewith whereby an arm holding a fan is caused to oscillate, and whereby the vibrations of the mechanism are so transmitted to the legs and feet of the doll as to 25 cause a shifting movement of the same upon the surface on which the doll stands, such shifting movement tending to cause the doll 30 to revolve around its vertical axis.

Another object of the invention is to provide 35 a novel arrangement and construction of the feet portions of the doll, whereby the doll receives a peculiar three point support, which is an important factor in producing the above mentioned revolving movement of 40 the doll.

Other objects of the present invention, not at this time more particularly enumerated, will be clearly understood from the following detailed description of the same.

45 With the objects of the present invention in view, the same consists, primarily, in the novel construction of mechanical doll hereinafter described; and, furthermore, the invention consists in the novel arrangements 50 and combinations of the various devices and parts, as well as in the details of the construction thereof, all of which will be hereinafter more fully described and claimed.

The invention is clearly illustrated in the accompanying drawings, in which:—

55 Figure 1 is a front elevation or face view of the novel doll provided with its clothing in place; and Figure 2 is a part front elevation and part transverse longitudinal section of the doll, with its clothing removed therefrom, and showing the internal operative mechanism.

Similar characters of reference are employed in all of the hereinabove described views, to indicate corresponding parts.

60 Referring now to said drawings, the reference character 1 indicates the body of the doll, which may be made of any suitable material, such as sheet metal, celluloid, papier mâché or other composition, and which is provided with a hollow or chambered interior 2. The body 1 is provided at its upper 65 end with a neck portion 3 upon which is fixed the head portion 4. The body 1 is provided at its lower end with leg receiving 70 sockets or openings 5. The body 1 is further provided at one side or shoulder 6 of its upper portion with an outwardly projecting upper arm portion 7 integrally and rigidly formed therewith, said upper arm portion 7 is hollow and open on its under side, the 75 same giving the effect of a raised arm portion. At the opposite side or shoulder 8 of the body 1 such an upper arm portion is omitted.

80 The reference character 9 indicates the leg portions of the doll, the upper ends of which are inserted into the sockets or openings 5, and secured at one side to the body by screws 10, or other suitable fastening means. The 85 leg portions 9 are provided respectively with the respective foot portions 11 and 12. The

foot portion 11 is provided with a heel portion 13 and toe portion 14 which are horizontally aligned so as to each contact with the 90 surface upon which the doll is stood. The foot portion 12 is also provided with a heel portion 15 and toe portion 16. The heel portion 15 is horizontally aligned with the heel portion 13 and toe portion 14 so as to 95 contact with the supporting surface, but the toe portion 16 is raised above the horizontal plane of the supporting surface engaging points of the heel portions 13 and 15 and the toe portion 14, as indicated by the dotted 100 line E, so that said toe portion 16 does not

engage the supporting surface upon which the doll is stood, and so that the doll is supported by a three point contact with said supporting surface, such points of contact 5 being provided by the heel portions 13 and 15 and the toe portion 14.

Arranged within the hollow or chambered interior of the body 1 is the frame 17 of a spring motor mechanism, the same being 10 supported by upright brackets 18 suitably attached thereto, and having downwardly extending portions 19 which penetrate the upper ends of said leg portions 9. Said motor mechanism comprises a spring arbor 15 20 journaled in the lower portion of said frame 17, said arbor projecting rearwardly through and exteriorly of the body of the doll so as to receive the attachment of an externally disposed winding key (not shown). 20 The reference character 21 indicates a spirally wound motor spring, the inner end of which is secured to said arbor 20, while the outer end 22 is anchored upon or fixed to a cross bar 23 which forms a part of the 25 frame 17. Journaled upon said arbor 20 is a driving gear 24 adapted to be rotated by said motor spring by any suitable arrangement commonly employed in clock spring movements. Journaled in said frame 17 30 above said motor spring is a spindle 25 upon which is fixed a pinion 26, which meshes with and is driven by said driving gear 24. Also fixed on said spindle 25 is an intermediate gear 27. Journaled in said frame 17 above 35 said spindle 25 is another spindle 28 upon which is fixed a pinion 29 adapted to mesh with and be driven by said intermediate gear 27. Fixed on said spindle 28 is a toothed escapement wheel 30. Journaled in 40 said frame 17 above said spindle 28 is an arbor 31 upon which is fixed an escapement dog or anchor 32, the latter having an impulse pallet 33 at one end, and a locking pallet 34 at the other end, which alternately cooper- 45 ate with said toothed escapement wheel 30. Connected with said escapement dog or anchor 32, so as to be oscillated by the escape- 50 ment mechanism, is a transverse rocking member 35, one end portion 36 of which is bent upwardly and outwardly to project outwardly through and beneath said upper arm portion 7 of the body 1. The outer extre- 55 mity 37 of said end portion 36 is doubled upon itself to extend inwardly across the outer front side of the body 1, and upon this extre- 60 mity 37 is fixed a fore-arm portion 38. Said extre- mity 37 terminates at the hand member 39 of said fore-arm portion 38, and has suitably secured thereto a fan member 60, attached in such a manner that the same appears to be held by said hand member 39. The opposite end portion 41 of said rocking member 35 is bent upwardly and inwardly, and secured to the free end thereof is a 65 weight 42.

The doll body is clothed in a kimona-like garment 43 having sleeves 44. One of said sleeves extends over the movable fore-arm portion 38. Secured within the opposite sleeve is a fore-arm portion 45 having a 70 hand member 46 which projects outwardly from the sleeve end.

The operation of the doll, constructed as above described, is as follows:—

The motor spring 21 is wound up, thus 75 storing its energy. The unwinding of the motor spring drives the driving gear 24, which imparts, through the intermediate train of pinions and gear 26, 27 and 29, a rotative movement to the escapement wheel 80 30. The rotation of the escapement wheel 30 acts upon the escapement dog or anchor 32 to produce an oscillation of the same, whereby the rocking member 35 is in turn oscillated. The rocking movement or oscil- 85 lation of said rocking member produces an up and down swinging movement of the fore-arm portion 38 and the associated fan member 40, whereby the geisha doll simulates the movements of fanning itself with 90 the latter. The oscillations of said fore-arm portion 38 and the associated fan member 40 are counter-balanced by the oscillation of the weight 42 carried by the opposite end of said rocking member. 95

The operation of the escapement mechanism causes an oscillation of said weight 42 producing vibrations which are transmitted through the bracket 18, and their extensions 19, to the leg members 9. By reason of the 100 above described three point contact support of the doll afforded by the arrangement of the feet portions 11 and 12, the foot portion 12, which has only its heel portion 15 in engagement with the supporting surface 105 upon which the doll stands, offers less resistance to movement than does the foot portion 11, which has both its heel portion 13 and toe portion 14 in engagement with the said supporting surface; consequently 110 there is a tendency of the foot portion 12 to slidingly displace itself under the influence of said vibration with the result that the doll tends to turn around on its vertical axis, producing a slow rotative movement 115 which simulates to a very pleasing degree a slow mincing step by step movement in imitation of a slow revolving dance movement. The described bodily rotation of the doll, coupled with the arm and fan move- 120 ment produces a very attractive and realistic effect, whereby the doll seems to perform in a manner well befitting the Japanese geisha it is intended to simulate. 125

I am aware that some changes may be made in the several arrangements and combinations of the various devices and parts, as well as in the details of the construction of the same, without departing from the scope of this invention as set forth in the 130

foregoing specification, and as defined in the appended claims. Hence, I do not limit my invention to the exact arrangements and combinations of the various devices and parts as described in said specification, nor do I confine myself to the exact details of the construction of said parts as illustrated in the accompanying drawings.

I claim:

10. 1. In a doll of the kind described, a hollow body, a spring motor mechanism having an escapement mechanism within said body, an external movable arm-portion having a fan member associated therewith, means actuated by said escapement mechanism for oscillating said movable arm portion and its fan member, and means for counter-balancing said arm-portion and its fan member.
20. 2. In a doll of the kind described, a hollow body, a spring motor mechanism having an escapement mechanism within said body, an external movable arm-portion having a fan member associated therewith, means actuated by said escapement mechanism for oscillating said movable arm portion and its fan member, leg portions connected with said body, feet portions connected with said leg-ports, said feet portions being arranged to provide a three point support for said doll when in standing position, and means interconnecting said spring motor mechanism with said leg portions whereby vibrations produced by the oscillation of said counterbalance weight are transmitted to the latter for the purposes described.
25. 5. In a doll of the kind described, a hollow body, leg-ports attached to said body, feet portions attached to said leg-ports, said feet portions each having heel and toe portions, the toe portions of one foot portion being raised above the plane of the surface upon which the doll is stood whereby the doll is normally supported by the heels and one toe portion of said feet portion, a spring motor device having an escapement mechanism within said body, a weight oscillated by said escapement mechanism, and means interconnecting said spring motor device with said leg portions whereby vibrations caused by oscillation of said weight are transmitted to the latter for the purposes described.
30. 6. In a doll of the kind described, a hollow body, leg-ports attached to said body, feet portions attached to said leg-ports, said feet portions each having heel and toe portions, the toe portion of one foot portion being raised above the plane of the surface upon which the doll is stood whereby the doll is normally supported by the heels and one toe portion of said feet portion, a spring motor device having an escapement mechanism within said body, means interconnecting said spring motor device with said leg-ports whereby vibrations of the former are transmitted to the latter for the purposes described, an external movable arm-portion having a fan member associated therewith, means actuated by said escapement mechanism for oscillating said movable arm portion and its fan member, and means counter-balancing said arm portion and its fan member.
35. 7. In a doll of the kind described, a hollow body having at one side an integral raised upper arm portion open on its under side, a spring motor device within said body, an escapement mechanism actuated by said spring motor device, a rocking member actuated by said escapement mechanism, said rocking member having an end portion extending beneath said upper arm portion and bent forwardly and inwardly at its extremity to project externally in front of said body, a movable fore-arm portion carried by said externally projecting extremity of said rocking member, a fan member associated with said movable fore-arm portion, and a counter-balance weight connected with the opposite end portion of said rocking member.
40. 5. 4. In a doll of the kind described, a hollow body having at one side an integral raised upper arm portion open on its under side, a spring motor device within said body, an escapement mechanism actuated by said spring motor device, a rocking member actuated by said escapement mechanism, said rocking member having an end portion extending beneath said upper arm portion and bent forwardly and inwardly at its extremity to project externally in front of said
45. body a movable fore-arm portion carried by said externally projecting extremity of said rocking member, a fan member associated with said movable fore-arm portion, a counter-balance weight connected with the opposite end portion of said rocking member, leg portions connected with said body, feet portions connected with said leg portions, said feet portions being arranged to provide a three point support for said doll when in standing position, and means interconnecting said spring motor mechanism with said leg portions whereby vibrations produced by the oscillation of said counterbalance weight are transmitted to the latter for the purposes described.
50. 5. 5. In a doll of the kind described, a hollow body, leg-ports attached to said body, feet portions attached to said leg-ports, said feet portions each having heel and toe portions, the toe portion of one foot portion being raised above the plane of the surface upon which the doll is stood whereby the doll is normally supported by the heels and one toe portion of said feet portion, a spring motor device having an escapement mechanism within said body, means interconnecting said spring motor device with said leg-ports whereby vibrations of the former are transmitted to the latter for the purposes described, an external movable arm-portion having a fan member associated therewith, means actuated by said escapement mechanism for oscillating said movable arm portion and its fan member, and means counter-balancing said arm portion and its fan member.
55. 7. 6. In a doll of the kind described, a hollow body, leg-ports attached to said body, feet portions attached to said leg-ports, said feet portions each having heel and toe portions, the toe portion of one foot portion being raised above the plane of the surface upon which the doll is stood whereby the doll is normally supported by the heels and one toe portion of said feet portion, a spring motor device having an escapement mechanism within said body, means interconnecting said spring motor device with said leg-ports whereby vibrations produced by the oscillation of said counterbalance weight are transmitted to the latter for the purposes described.
60. 7. 7. In a doll of the kind described, a hollow body, leg-ports attached to said body, feet portions attached to said leg-ports, said feet portions each having heel and toe portions, the toe portion of one foot portion being raised above the plane of the surface upon which the doll is stood whereby the doll is normally supported by the heels and one toe portion of said feet portion, a spring motor device having an escapement mechanism within said body, means interconnecting said spring motor device with said leg-ports whereby vibrations produced by the oscillation of said counterbalance weight are transmitted to the latter for the purposes described.
65. 7. 8. In a doll of the kind described, a hollow body, leg-ports attached to said body, feet portions attached to said leg-ports, said feet portions each having heel and toe portions, the toe portion of one foot portion being raised above the plane of the surface upon which the doll is stood whereby the doll is normally supported by the heels and one toe portion of said feet portion, a spring motor device having an escapement mechanism within said body, means interconnecting said spring motor device with said leg-ports whereby vibrations produced by the oscillation of said counterbalance weight are transmitted to the latter for the purposes described.

1
ing said spring motor device with said leg portions whereby vibrations of the former are transmitted to the latter for the purposes described, a rocking member actuated by 5 said escapement mechanism, said rocking member having one end portion externally disposed relative to said body, a fore-arm portion fixed on said external portion of said rocking member, a fan-member associated 10 with said fore-arm portion, and a counter-balance weight fixed to the opposite end of said rocking member.

8. In a doll of the kind described, a hollow body, leg-portions attached to said body, feet 15 portions attached to said leg portions, said feet portions each having heel and toe portions, the toe portion of one foot portion being raised above the plane of the surface upon which the doll is stood whereby the 20 doll is normally supported by the heels and one toe portion of said feet portion, a spring motor device having an escapement mechanism within said body, means inter-connecting said spring motor device with said leg

portions whereby vibrations of the former 25 are transmitted to the latter for the purposes described, said hollow body having at one side an integral raised upper arm portion open on its under side, a rocking member actuated by said escapement mechanism, said 30 rocking member having an end portion extending beneath said upper arm portion and bent forwardly and inwardly at its extremity to project externally in front of said body, a movable fore-arm portion carried 35 by said externally projecting extremity of said rocking member, a fan member associated with said movable fore-arm portion, and a counter-balance weight connected 40 with the opposite end portion of said rocking member.

In testimony, that I claim the invention set forth above I have hereunto set my hand this 12th day of May, 1921.

DAVID ZAIDEN.
